Specification of Letters Patent. Patented Apr. 12, 1921.

Application filed February 15, 1919. Serial No. 277,252.

To all whom it may concern:

Be it known that I, JAMES H. BOYE, a citizen of the United States, residing at Chicago, in the county of Cook and State 5 of Illinois, have invented certain new and useful Improvements in Commodity-Cabinets, of which the following is a specification.

This invention relates to commodity cabinets for use by merchants and dealers in storing various small articles of merchandise in a manner enabling them to be readily accessible to and easily found by the merchant in making sales and to prevent 10 confusion, mistakes, and loss of time in the finding of small articles. While the invention has been more particularly designed to facilitate the retail handling of sewing machine accessories, such as needles, bobbins, 15 shuttles and the like, yet it is readily adaptable without change of structural principle, to the handling of supplies, accessories and small parts of other machines, as well as independent small articles such as plain 20 sewing needles, crochet needles, and the like, and hence in its broader aspects is not limited to a commodity cabinet for sewing machine parts and accessories.

The cabinet of the present invention is 25 in the nature of an improvement upon the cabinet forming the subject matter of Letters Patent No. 1,294,761, granted to me on the 18th day of February, 1919, and in the specification of said Letters Patent, to which 30 reference may be had, I have set forth fully the principal purpose and advantages and the manner of use of a cabinet of this type. The principal object of the present invention is to improve the cabinet of my afore- 35 said patent in certain structural and functional features, such as increased commodity-carrying capacity, greater ease of access to its holders and compartments, greater protection to the goods from dust 40 and dirt, and improved supporting and locking means for the swinging commodity-holders.

Still other objects and advantages of the invention will be apparent to manufacturers 45 and users of vending cabinets and others skilled in the art from the following detailed description, taken in connection with the accompanying drawings, in which I

have illustrated one operative and practical embodiment of the invention, and wherein,— 55

Figure 1 is a top plan view of the cabinet;

Fig. 2 is a front elevation, as viewed from the lower side of Fig. 1;

Fig. 3 is a bottom plan view; 60

Fig. 4 is a horizontal section on the line 4—4 of Fig. 5;

Fig. 5 is a vertical section taken on the offset line 5—5 of Fig. 4;

Fig. 6 is a sectional detail taken on the 65 line 6—6 of Fig. 1.

Referring to the drawings, 10 designates the top wall and 11 the side wall of a substantially circular sheet metal casing, the same being formed with four integral hollow legs 12 by which the cabinet rests on a counter or table. In the front portion of the side wall 11, midway between adjacent legs 12, is formed a rectangular opening 13, the vertical sides of which are preferably 70 equipped with stiffening border frames 14. Secured to the upper side of the top wall 10 and extending diametrically from front to rear thereof is a stiffening plate or strip 15 formed with a widened substantially circular central portion 15', as clearly shown 75 in Fig. 1. At a point diametrically opposite the front opening 13 the top wall 10 and stiffening strip 15 are formed with registering rectangular openings that are preferably covered by a glass window 16, the frame 17 of which is detachably secured to the stiffening strip 15 by screws 18.

Strongly secured to and centrally of the under side of the top wall 10 of the casing 90 is a circular plate 19 (Fig. 5) which serves as an auxiliary stiffener to the top wall 10 and also as a base plate for a depending spindle or post 20 integral therewith or rigidly secured thereto. Mounted to turn on this spindle 20 is a skeleton hub 21 having spaced upper and lower bearings 21^a and 21^b; and secured to this hub by rivets 22 is a rotary carrier-disk 23 which has a diameter approximately equal to the internal 95 100 diameter of the cabinet casing. On the lower end of the spindle 20 is a disk 24 forming a rest or support for the hub 21 and itself held in place by a nut 25 and lock nut 26; and from the disk 24 extend 105 four brace-rods 27 to the lower ends of the

legs 12, as most clearly shown in the bottom plan view, Fig. 3. The two front legs are also preferably connected by a tie-rod 28, on account of the weakening of the front 5 wall by the opening 13.

Mounted on the upper side of the carrier-disk 23 are a group, herein shown as eight, of radially disposed drawer-housings 29, in each of which is slidably mounted a drawer 30. In the present instance each drawer is divided by a longitudinal partition 31 into a compartment 32 designed to hold small machine parts such as bobbins, shuttles, and the like, and a relatively long narrow and 10 deep compartment 33 designed to contain crochet needles and analogous articles. To facilitate withdrawal of the latter, the bottom wall and outer side wall of this compartment are formed with registering trans- 15 verse slots 34 and 35 which accommodate the thumb and finger in removing the articles. The drawer is yieldably locked in place by a spring detent consisting, as herein shown, of an elastic strip 36 secured at its ends to 20 the outer side wall of the housing 29 and formed with a central protuberance 37 that enters a pair of registering holes 38 and 39 formed in said side wall and the adjacent 25 wall of the drawer, all as clearly shown in 30 Fig. 4. The outer ends of the side walls of the drawer-housings are notched as shown at 40 (Fig. 5) to facilitate the grasping of the forward end of the drawer in withdrawing the latter.

35 41 designates each of four generally sector-shaped plates, each of which is formed with a plurality of round apertures 42 adapted to receive and support the shoul- 40 dered tube-like boxes or bottles 43 in which sewing machine needles are customarily packaged for the market. Each of these commodity holders 41 is preferably formed with outer and inner depending stiffening 45 flanges 44 and 45, and each holder is piv- 50 otally suspended centrally of its outer edge from the rotary carrier-disk 23. As herein shown there is secured to the upper side of each holder-plate a bail-shaped strip 46, the forward upwardly bent end of which is 55 connected by a pivot pin 47 to the carrier 23, while the rearward upwardly bent end has a horizontal terminal portion 48 that overlies and rests upon a supporting lip or flange 49 secured to the under side of the 60 carrier-disk 23; this lip or flange 49 having an arcuate form and being concentric with the pivot 47. By this means the holder-plate 41 is strongly supported from the carrier-disk 23 at both its front and rear. The 65 flanges 49 also serve to stiffen the carrier-disk. It will be noted that each complete holder 41 is symmetrically constructed with reference to its median radial line or axis, so that each is in effect a double receptacle or holder, the portion thereof lying on each

side of the median radial line being de- 70 signed to hold the goods of a single manu- 75 facturer.

By rotating the carrier-disk 23 through the means hereinafter described, any one of the drawers, and the directly underlying half of the perforated plate may be brought opposite the opening 13 of the casing. When brought to this position the drawer may be readily drawn out through the opening to obtain access to the contents thereof, and the underlying pivoted holder may also be swung out through the opening, as indicated by dotted lines in Fig. 3, so as to obtain access to the goods carried thereby. 80 In order to avoid accidental swinging movement of the pivoted holders, which might interfere with the turning of the carrier, I provide manually releasable spring-latches 50 (Fig. 3) on the opposite 85 side edges of each holder-plate, the latches of adjacent holder-plates coöperating with depending stops 51 secured to the carrier-disk 23. Each latch bar 50 has a radially off-set lug 50' by which it may be retracted 90 from the stop 51 by the thumb and finger of the operator.

To the vertical edges of the stiffening strips 14 at the vertical sides of the opening 13 are pivoted a pair of outwardly swinging doors 52, by which the opening is normally closed to exclude dust and dirt from the interior of the cabinet. The doors are yieldably held in closed position by a catch mem- 95 ber 53 secured to the forward end of the stiffening plate 15 and formed with a pair of over-hanging spring detents 53' adapted to independently engage with dents or de- 100 pressions 54 in the upper edges of the doors 52. By this device both of the doors will 105 be held closed even though their upper edges should not be in perfect horizontal alinement.

Referring next to the means for actuating the carrier-disk 23 so as to bring any 110 pair of the eight pairs of commodity holders opposite the casing opening, this mechanism is substantially identical with the corresponding mechanism disclosed in my former patent, above referred to, and, briefly 115 described, comprises the following parts. 55 designates a pinion that is loose on the spindle 20 and is secured to the upper hub bearing member 21^a of the carrier. With this pinion meshes a gear 56 that is fast on the lower end of a short shaft 57 that is journaled in the top wall 10 and its stiffening plate 15'. Fast on the shaft 57, just above the plate 15', is a radial actuating arm 58 on the free end of which is an upstanding finger-hold 59. On the free end of the arm 58 is also formed a forwardly directed pointer-finger 60, and in rear of the latter is an upwardly off-set rearwardly directed pointer-finger 61. Secured to the stiffening 120 125 130

plate 15 is a segment plate 62 that overlies all except the free end and pointers of the arm 58. This segment plate is formed with shoulders or stops 63 that limit the swinging movements of the arm 58, and, between said stops, with a series of equally spaced notches 64 in its raised edge. These notches are engaged by a spring-pressed manually retractable locking dog or pawl 65 mounted 10 on the finger-hold 59. The locking notches 64 correspond in number with the radial groups of commodity compartments of the carrier (eight being herein shown).

On the top of the several drawer-housings, are charts containing the names of eight leading sewing machine factories 15 which make not only the machines going under the names of these factories but also practically all of the many so-called stenciled machines which go under the trade names of different dealers; and on these 20 charts also appear alphabetical symbols A to H inclusive, which are identified with the respective factory names. Preferably also 25 each chart discloses catalogue prints or cuts of the principal small machine parts or accessories, such as shuttles, bobbins, and the like, made by the respective factories; and these charts are so arranged that in any 30 and all positions of the rotary carrier the chart which shows through the window 16 relates to and identifies the goods contained in the commodity holders which are opposite the opening 13 and in accessible position. 35 On the stiffening plate 15' is a corresponding index consisting of the letters A to H inclusive grouped in arcuate form opposite the locking notches 64. When the actuating arm is swung to carry the pointer 60 opposite any letter of this index, the correspondingly identified chart is brought beneath the window 16, and the pair of commodity 40 holders containing goods identified by said chart are brought opposite the opening 13 and may be withdrawn through the latter, when the doors 52 are opened, to afford easy 45 access to the goods which they contain. At the same time these compartments are held in delivery position at the opening 13 by the 50 dog 65 which locks the rotary carrier against turning.

On the free edge of the segment plate 62 are two indexes, one of different sizes of hand needles which may be contained in the 55 drawer compartments 32, and the other of different sizes of crochet needles which are designed to be contained in the drawer compartments 33. The pointer 61 co-operates with these indexes in the same way that 60 the pointer 60 co-operates with the alphabetical index A to H inclusive.

As hereinabove mentioned, there are in the sewing machine industry a limited number of makers of different machines (eight 65 being assumed in the present case) and

there are many hundreds of machines going under as many different trade names or retail dealers, and all manufactured by this limited number of makers. Hence, a customer may go to her dealer to buy a needle, 70 bobbin, shuttle or other accessory, for her machine, and he, not knowing the factory source of that particular machine, may be at a loss to supply her with a part that will fit. To provide for this contingency there 75 is provided on the top of the cabinet casing an extensive alphabetical name index of all the principal and most extensively used machines sold under various names, this index being arranged in curved concentrically 80 grouped columns 66, as shown in Fig. 1. On one side of each column 66 is a parallel column 67 containing the same commodity-holder identifying symbols (letters A to H inclusive) that are employed in the central 85 index, these symbols appearing directly opposite the names in columns 66. By the use of this index the factory source of any given machine is readily ascertained, and the correct supplies for the machine obtained, as more fully explained in detail in my Letters Patent hereinabove identified. I have, however, in the present device provided an improvement in this feature, as 90 follows. Since the list of names of the different machines is changing every little while, some names becoming obsolete and new names appearing, it is necessary occasionally to revise the alphabetical indexes of names and their source identifying symbols appearing in the columns 66 and 67. I therefore print these indexes, not on the 95 top wall of the cabinet casing, but on a removable disk or plate which may readily be replaced by a new one. This is most conveniently effected, as shown in Figs. 1 and 6, by printing these indexes on a pair of approximately semi-circular disks or plates 68, the inner edges of which may underlie the side edges of the stiffening plate 15, while 100 their outer edges are securely fastened to the top of the casing by curved clamp-strips 69 and screws 70. By simply removing these clamp strips, the index cards or plates may be withdrawn and replaced by new 105 ones brought up to date.

I have also herein illustrated two further features of great utility in a commodity cabinet of this character which are disclosed and claimed in my aforesaid Letters Patent, 110 and which I will briefly describe. On the upper face of the segment plate 62 is a needle chart consisting of radially arranged exact-size prints 71 of the outer (point and eye portions) of the different sewing machine 115 needles made by the different manufacturers. The shaft 57 extends upwardly through the segment plate 62, and fast on its upper end is a radial arm 72, the upper surface of which is channeled to support the shank 120

of a sewing machine needle laid therein. If a customer, ignorant of the manufacturing source of her machine, can produce a sample needle, this latter is laid on the arm 52 with its shank end abutting against the inner end of the channel, and the arm 58 is swung until the over-hanging point or eye portion of a needle exactly registers with and matches one of the chart prints 71. This brings to the opening 13 a commodity holder containing needles identical with the sample.

Again, it sometimes happens that the owner of a machine not listed on the name index has no sample needle, or desires to order some machine part not carried in stock by the cabinet. To take care of this situation I have provided an additional means for identifying the factory source of any machine, based on the fact that practically all of the different makes of sewing machines have detachable presser-feet with bifurcated or forked shanks, all of which latter differ in specific size and shape. In the top surface of the stiffening plate 15' there are formed a series of die-impressions 73 of the forked shanks of all the different makes of presser-feet, these impressions being grouped in arcuate form outside of and opposite the alphabetical index A to H inclusive, in the manner clearly shown in Fig. 1. The customer brings to the store the presser-foot of her machine. The dealer applies it to the various dies; and the alphabetical index letter pertaining to the die which the presser-foot fits identifies the source of manufacture in the manner already described, and thus enables the desired article to be obtained from the cabinet or from the factory.

As I have already stated, in its general organization and arrangement, and in the functions performed and advantages secured the commodity cabinet of my present invention is largely based upon and follows the commodity cabinet disclosed in and covered by my aforesaid Letters Patent No. 1,294,761; but in several details of structure and or-

ganization my present cabinet embodies substantial improvements upon the cabinet of the aforesaid patent, through which the stated objects of the invention are secured, and which improvements are set forth in the appended claims, as follows.

I claim:

1. In a commodity cabinet, the combination of a casing having a side wall formed with an opening, a carrier rotatably mounted in said casing, a group of radially sliding drawers mounted on the upper side of said carrier, a group of swinging commodity holders each pivotally mounted on the under side of said carrier at a point midway between two adjacent drawers, whereby any one of said drawers and the underlying holder may be withdrawn through said opening when brought opposite the latter.

2. In a commodity cabinet, the combination of a casing having a side wall formed with an opening, a carrier disk rotatably mounted in said casing, a group of radially sliding drawers mounted on the upper side of said disk, and a group of generally sector-shaped commodity holders pivoted centrally of their outer edges to the under side of said carrier disk midway between two adjacent drawers on the latter.

3. In a commodity cabinet, the combination of a casing having an opening in its side wall, a carrier rotatably mounted in and centrally of said casing and of approximately the internal diameter of the latter, a plurality of generally sector-shaped commodity-holders pivotally suspended centrally of their outer edges from and around the periphery of said carrier, a series of arcuate lips or flanges on said carrier each concentric with the pivot of one of said commodity-holders, and suspension members each secured to one of said commodity-holders and at its upper end resting upon and slidably engaged with one of said lips or flanges.

JAMES H. BOYE.
